UNITED STATES PATENT OFFICE

CHARLES H. LEINERT, OF CHICAGO, ILLINOIS

VALVE FOR COMPRESSORS

Application filed December 2, 1929. Serial No. 411,154.

This invention relates to a valve, either suction or discharge, which is particularly adapted for compressors, blowing engines, and the like. It comprises a seat member, a stop plate and an intermediate reciprocable valve plate, together with spring means by which the valve is urged toward its seat. The present improvements are concerned primarily with the spring means which permit of an increased volume of air passing through and around the valve plate due to larger area of the ports therein, and of a higher lift of the valve plate from its seat.

A suggestive embodiment of the invention is set forth in the accompanying drawings wherein—

Figure 1 is an axial section through the valve assembly;

Fig. 2 is a top plan view of the valve plate per se; and

Fig. 3 is a detail in section on line 3—3 of Fig. 2.

The present valve assembly which is adapted for attachment directly to a compressor wall or to a cage which is carried thereby, includes a seat member A with which is associated a stop plate B detachably connected to the seat as through the medium of a bolt C the head 10 of which may rest against the outer side of the stop plate, as shown. Interposed between these parts is a distance piece D which may also serve as a centering means for a reciprocable valve plate E in the form of a disk against which a constant pressure is exerted by spring means 21, the disk being thereby held normally upon its seat. The parts just enumerated are the principal ones which enter into the construction of this valve, but they are specially formed to cooperate with each other in a peculiar manner as will now be set forth.

The body of the seat member comprises a hub 11, an outer rim 12 and connecting webs or spokes 14 between which are arcuate-shaped ports or openings having an aggregate area which, by preference, is the maximum obtainable with due regard for safety and strength. The member A is formed with a seat comprising ribs 15 and 16 extending upwardly from the hub and rim. The bolt C

which I have suggested as a convenient means for attaching the stop plate to the seat member permits these parts to be readily disconnected whenever desired. The distance piece D which is in the form of a ring or bushing is disposed with one end against the hub of the seat member and with its other end against a hub 17 that is formed centrally of the stop plate. This bushing extends freely through the center portion of the valve plate, but out of contact therewith, so as to offer no frictional resistance to the reciprocations thereof.

The stop plate which is of a diameter about the same as the seat member is provided with inner and outer depending annular walls 19 and 20 respectively. The lower edges of these walls terminate at a predetermined distance from the seat member, and constitute an abutment against which the valve plate strikes when lifted off its seat to the maximum distance. In such lifted position of the valve plate, air entering through the ports between the spokes of the seat member may pass on around the edges of the valve plate for delivery to a desired point. The valve plate is normally held upon its seat by a plurality of like spring means formed integrally with itself, and tempered to a desired degree of tension.

As shown best in Fig. 2, the central portion of the valve plate is cut out to provide an inner circular edge adjacent which are arms each of which comprise three main portions which I will term the fulcrum section 20, the radial section 21, and the free end section 22. Each fulcrum arm section which terminates in a head 23 integral with the valve plate at a distance of 120° from the remaining heads, is extended around in the same direction in general conformity with the circular inner edge of the valve plate. For the major portion of its length, as defined by two shoulders 24, the fulcrum section is of reduced thickness, the purpose being to increase the flexibility of the spring at this point. Each spring arm which continues through the radial section and thence through its free end section in a gradual rise, is in effect doubled upon itself so as to pre-

sent its extremity 120° removed from the corresponding ends of the other two arms. The free ends of the springs are furthermore located close to and behind the heads 23 so that the fixed end of each spring acts as a true fulcrum when the spring is subjected to pressure. At the end of each spring arm is an upturned lip 25 pointed to enter a cone-socket provided for its reception in the under 10 side of the stop plate.

The spring means just described is triplicated in the construction shown; that is, three spring arms each alike are provided for the valve plate, the arms presenting portions close 15 to each other but not overlapping, and each occupying a portion of the space centrally of the valve plate within an arc of less than 120°. The effect of this arrangement is to provide three contact lips 25 each situated 120° from the others and each adapted, when seated against the stop member, to maintain the valve plate centrally upon its seat. The space between the free ends of the arms is ample for the hub 17 of the stop plate to 20 pass therethrough, so that no friction will occur during reciprocations of the valve plate. The arrangement of the spring arms furthermore is one which provides for the maximum area of openings in the center region of the plate. It will be noted that the valve plate springs are confined within an area that is inside of the inner depending wall 19 of the stop plate. This wall engages 25 with the valve plate just to the outside of the springs (see Fig. 1), and because of this relationship of the parts, the airflow, when the valve is off its seat, is directed away from the springs past the outer edges of the stop plate.

40 The present valve construction is advantageous in that the springs being formed integral with the valve plate require no separate mounting or assembly. They are entirely frictionless, and because of their arrangement and disposition are endowed with unusual length, thereby making possible a higher lift of the valve plate with a consequent increase in capacity.

I claim:

60 1. In a valve of the kind described, the combination with a seat member and stop plate in spaced relation, of a valve plate reciprocable therebetween having a central opening into which is extended plurality of spring arms integral with the valve plate and each doubled upon itself and proceeding in a gradual rise to present an end in loose engagement with the stop plate.

65 2. In a valve of the kind described, the combination with a seat member and a stop plate in spaced relation, of a valve plate reciprocable therebetween having a central opening which defines an inner edge adjacent which are extended three integral springs with free ends, each spring being disposed initially in

the same direction thence radially and thence reversely through a continuous rise to present their ends loosely against the stop plate 120° apart.

3. In a valve of the kind described, the combination with a seat member and a stop plate in spaced relation, of a valve plate reciprocable therebetween having a central opening adjacent which are formed three integral springs each having a portion extending in the same direction adjacent the inner edge of the valve, thence in a radial direction, and thence in a reverse direction through a continuous rise, the ends of the three springs being free and upturned and pointed for loose engagement with the stop plate at distances of 120 degrees apart. 70 75

4. The combination with a seat member and a stop plate in spaced relation, of a valve plate reciprocable therebetween, the valve 80 plate being provided with a plurality of integral springs free at one end and each executing a reverse bend and proceeding through a continuous rise to present their several free ends at points equidistantly apart for loose engagement with the stop plate.

5. The combination with a seat member, a stop plate and a central connecting means for spacing the one a fixed distance from the other, of a centrally apertured valve plate reciprocable between the seat member and stop plate, the valve plate being provided with three integral spring arms each having a curved portion adjacent the inner periphery of the plate, a radial portion, and a return 95 portion which terminates in a bearing point adapted to engage with the stop plate, the return portion of each spring arm being free 100 of engagement with the central connecting 300 means. 105

6. The combination with a seat member and a stop plate in spaced relation, of a valve plate reciprocable therebetween having extended integrally therefrom a plurality of spring arms each free at one end proceeding 110 in a gradual rise and terminating in bearing points for engagement with the stop plate, the fulcrum portion of each spring arm adjacent its connection with the valve plate being of reduced thickness. 115

7. The combination with a seat member and a stop plate in spaced relation, of a valve plate reciprocable therebetween having a plurality of integral spring arms each proceeding through an initial thin curved portion, 120 thence through a radial portion, and finally through a return portion all disposed in a gradual rise to present equidistant ends for engagement with the stop plate.

8. The combination with a seat member and a spaced stop plate, of a valve plate reciprocable therebetween having spring arms joined integrally thereto with return bends presenting their free ends rearwardly of their points of juncture with the valve plate. 125 130 135

9. The combination with a seat member and a spaced stop plate, of a valve plate reciprocal therebetween having a plurality of spring arms free at one end and joined integrally to the valve plate, each executing a return bend and proceeding in a gradual rise to present a free end in engagement with the stop plate at a point which is close to its juncture with the valve plate.

5 10 In testimony whereof, I have hereunto set my hand this 30th day of November, 1929.

CHAS. H. LEINERT.
